UNITED STATES PATENT OFFICE.

WALTER FREMONT OSBORNE, OF WAGON MOUND, NEW MEXICO.

AEROPLANE.

1,387,899.

Specification of Letters Patent. Patented Aug. 16, 1921.

Application filed November 26, 1919. Serial No. 340,743.

To all whom it may concern:

Be it known that I, WALTER FREMONT OSBORNE, a citizen of the United States, and a resident of Wagon Mound, in the county of Mora and State of New Mexico, have invented certain new and useful Improvements in Aeroplanes, of which the following is a specification.

My present invention relates generally to aeroplanes and more particularly to an aeroplane embodying means by which to counteract crossing or counter air currents, as well as to neutralize to a considerable extent the effect of striking air pockets and my invention has therefore, for one of its objects, the provision of means adapted to act to some extent as a stabilizing arrangement.

My invention also has for its object the provision of an arrangement by which to assist in both climbing and descent of aeroplanes as well as to increase its normal capabilities as to a safe maximum speed and an arrangement which will be highly useful in landing to prevent disastrously heavy contact upon alighting.

With these general objects in mind, and also further objects which relate for the most part to the details of construction and arrangement whereby the invention may be attached to aeroplanes now in use, my improvements will be better understood from the following description of its details, reference being made to the accompanying drawings which form a part of this specification, and in which,

Figure 1 is a side view partly broken away and in section,

Fig. 2 is a top plan view with the upper wing broken away and certain of the parts of my invention also broken away and in section,

Fig. 3 is a front elevation,

Fig. 4 is a sectional view through one of the gear cases taken substantially on line 4-4 of Fig. 2,

Fig. 5 is a transverse vertical section taken on line 5-5 of Fig. 1,

Fig. 6 is an enlarged detail plan of certain of the connections,

Fig. 7 is an enlarged detail horizontal section through certain other connections,

Fig. 8 is a detail vertical section through certain of the connections taken substantially on line 8-8 of Fig. 1,

Fig. 9 is a detail vertical section taken adjacent to one of the supplemental propeller shaft adjusting cranks, and

Fig. 10 is a transverse vertical section taken through certain of the driving connections substantially on line 10-10 of Fig. 2.

Referring now to these figures, I have shown in Figs. 1 to 3 inclusive an aeroplane of which the fuselage appears at 15, the upper and lower wings at 16 and 17 respectively, the landing skid at 18 and the main propeller at 19 mounted as usual upon the forwardly extending end of the motor crank shaft 20.

In accordance with my improvements, the motor crank shaft is extended rearwardly as seen at 21 in Fig. 2 and has certain geared connections as presently described for the driving of the inner or rear sections 22 of a pair of supplemental propeller shafts, the outer or forward sections 23 of which support forward supplemental propellers 24, the latter of similar size to one another and disposed upon relatively opposite sides of, and at equi-distant points from, the main propeller 19.

From Figs. 1 and 2, it will be noted that these supplemental propellers 24 are disposed somewhat to the rear of the main propeller 19, although extending forwardly of the wings 16 and 17 at opposite sides of the fuselage and by reference to Fig. 3 it will be noted that the axes of the two supplemental propellers are normally disposed in the same horizontal plane with the axis of the main propeller.

The two sections 22 and 23 of each of the shafts supporting the supplemental propeller 24, are connected to one another by universal joints 25 so that the forward sections 23 to which the supplemental propellers are directly connected, can be shifted in various directions, upward and downward movement to and below a horizontal position being particularly to be desired in order that the supplemental propellers may assist in quick climbing and quick descent of the machine, both under effective control and both attended by the stabilizing effect the propellers will naturally have in view of their location as described with respect to the main propeller. It will moreover be observed that in landing, for which the supplemental propellers may have in the first instance been turned downwardly, quick shifting of the supplemental propellers to a position above the horizontal will materially assist in proper alighting in order to avoid disastrously heavy contact with the ground.

For this purpose the connections in so far as the driving of the supplemental propellers is concerned may include the gear 26 secured upon the rearwardly extending 5 end of the crank shaft 21 in engagement with gears 27 and 28 respectively mounted upon shafts 29 and 30, shaft 29 being directly geared by bevel gears 31, to a right angular shaft 32 which is in turn directly 10 geared by bevel gears 33 to the inner or rear end of the inner rear section 22 of one of the supplemental propeller shafts.

The other shaft 30 is geared by gears 34 to a shaft 35 and the latter is geared by beveled 15 gears 36 to a right angular shaft 37 in turn directly geared by bevel gears 38 to the inner rear end of the inner rear section 22 of the other supplemental propeller shaft.

In this way, the power from the motor is 20 supplied to the supplemental propellers to drive the latter in the same direction as the main propeller 19.

The gears 26, 27 and 28, gears 34 and also the bevel connecting gears 31, 33, 36 and 38 25 may be housed within gear casings through which the respective shafts have bearing, so that the gears may be run in oil to avoid excessive wear and heating, which would otherwise be brought about in view of the 30 high speed of movement.

The gear casing of the gears 26, 27 and 28 appears at 39, a gear casing 40 houses gears 31 and gear casings 41 and 42 respectively 35 house the beveled gears 33 and 38 while a single gear casing 43 will be disposed to house the gears 34 and 36 connecting shafts 30, 35 and 37.

For the control of the supplemental propellers, a control shaft 44 is mounted in 40 bearings 45 to move lengthwise beneath the fuselage 15, from which connections may be had to the supplemental propeller shafts without interfering with the other controls of the machine, these connections to include 45 a pair of diverging forwardly extending connecting rods 46, in jointed sections, the rear ends of which rods are connected to the shaft 44 as at 47, and the forward ends of which are adjustably connected to the depending apertured arms of bell-crank-levers 50 48, the upper ends of the latter of which are secured to the inner ends of controlling studs 49, through the outer ends of which the inner portions of the outer sections 25 of the 55 supplemental propeller shaft are journaled. These controlling studs 49 projecting as they do in a lateral direction from the supplemental propeller shafts are movable to various positions below the outer portions of the 60 supporting brackets 50, in which the fulcrum points of the bell-cranks 48 are supported. These brackets extend from opposite sides of the fuselage 15 and the inner ends thereof are secured to this fuselage.

The operator controls movement of the 65 control shaft 44 through a connecting rod 51, the lower rear end of which is pivotally connected to an upright lever 52, and the upper forward end of which, within the fuselage, is pivotally connected to the lower 70 end of a control lever 53, having a latch mechanism 54 in engagement with a notched quadrant 55.

This quadrant is rigidly mounted within the fuselage adjacent to the operator's seat 75 so that the propeller carrying sections of the supplemental propeller shafts may thus be held in various positions of adjustment throughout the angular range of movement 80 of the shafts.

It is thus obvious that my invention proposes an arrangement capable of ready manipulation in order to assist the aeroplane in either climbing or descent, as well as an arrangement which in its normal position will 85 not only assist in the propulsion of the machine but will have in its ordinary operation, a stabilizing effect which will avoid danger of side slipping through the air and will have a decided tendency to permit of more 90 ready effective action of the machine under the usual controls.

I claim:—

1. A pair of supplemental propellers for aeroplanes, shafts upon the forward ends of 95 which said propellers are mounted, having flexible joints intermediate their ends, driving connections leading to the rear ends of the shafts, a pair of supporting brackets, bell cranks having pivots on the brackets 100 substantially in line with the said joints of the propeller shafts, studs outstanding from one end of the bell cranks and movably engaging and supporting the propeller shafts forwardly of their joints, and adjusting connections leading to the opposite ends of said bell cranks, as described.

2. A pair of supplemental propellers for aeroplanes, shafts upon the forward ends of 110 which said propellers are mounted, having flexible joints intermediate their ends, driving connections leading to the rear ends of the shafts, a pair of supporting brackets, bell cranks having pivots on the brackets 115 substantially in line with the said joints of the propeller shafts, studs outstanding from one end of the bell cranks and movably engaging and supporting the propeller shafts forwardly of their joints, and adjusting connections leading to the opposite ends of said 120 bell cranks, and including a lengthwise shiftable shaft, arms pivoted at one end to said adjusting shaft and diverging therefrom to the other ends of said bell cranks, and normally locked means for manually shifting 125 said adjusting shaft.

WALTER FREMONT OSBORNE.
